Primary Examiner — George D. Kirschbaum*Assistant Examiner* — Kendra Leslie Hamilton(74) *Attorney, Agent, or Firm* — Pauly, DeVries, Smith & Deffner LLC(57) **CLAIM**

The ornamental design for a bowl lid, as shown and described.

DESCRIPTION

FIG. 1 is a perspective view of the top back side of a bowl lid.

FIG. 2 is a perspective view of the bottom right side of the bowl lid.

FIG. 3 is a top plan view of the bowl lid.

FIG. 4 is a bottom plan view of the bowl lid.

FIG. 5 is a left side elevation view of the bowl lid; and, FIG. 6 is a right side elevation view of the bowl lid.

The broken lines in the drawings illustrate portions of the bowl lid that form no part of the claim.

1 Claim, 5 Drawing Sheets(56)
